(57) **CLAIM**

The ornamental design for a trampoline as shown and described.

DESCRIPTION

1. Trampoline

1.1 : Perspective

1.2 : Front

1.3 : Back

1.4 : Left

1.5 : Right

1.6 : Top

1.7 : Bottom

1.8 : Perspective

1. The name of this design product: trampoline; 2. The purpose of this design product: a sports equipment; 3. The design key points of this design: the shape of the frame structure and the shape of the doors of the safety net; 4.

(Continued)

Pictures or photos that best illustrate the key points of the design: three-dimensional drawings.
